Patented Aug. 29, 1961

191,201

PICTURE HANGER

Walter Bell, Monroe, N.Y., assignor to Star Precision Devices, Inc., Mountainville, N.Y., a corporation of Delaware

Filed Dec. 29, 1960, Ser. No. 63,395

Term of patent 14 years

(Cl. D17—12)

I claim:

The ornamental design for a picture hanger, substantially as shown.
